CLAIM

The ornamental design for a bag as shown and described.

DESCRIPTION

FIG. 1 is a perspective view of a bag showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 1; and,

FIG. 11 is a partial enlarged view of portion 11 in FIGS. 2; and,

FIG. 12 is a perspective view of the bag of FIG. 1, shown in an in-use state.

The evenly-dashed broken lines depict portions of the bag and form no part of the claimed design.

The dot-dash broken lines shown in FIGS. 1-2 and 9-11, which form no part of the claimed design, encircle portions of the bag that are illustrated in enlargements.

The dot-dot-dash broken lines, shown in FIGS. 1-4 and 12, represent portions of the bag and form part of the claimed design.

1 Claim, 12 Drawing Sheets
